Primary Examiner — Prabhakar Deshmukh(74) *Attorney, Agent, or Firm* — QuickPatents, LLC; Kevin Prince(57) **CLAIM**

I claim the ornamental design for a pool cue holder, as shown and described.

DESCRIPTION

FIG. 1 is a perspective view of a pool cue holder showing my new design;

FIG. 2 is a front elevational view thereof, the rear, left and right elevational views are mirror image thereof;

FIG. 3 is a top plan view thereof; and,

FIG. 4 is a bottom plan view thereof.

The broken lines indicate environmental matter and form no part of the claimed design.
